US0D1113905S

(12) **United States Design Patent** (10) **Patent No.:** **US D1,113,905 S**
(45) **Date of Patent:** **** Feb. 17, 2026**

(54) **OUTDOOR ELECTRONIC DISPLAY ASSEMBLY**

(71) Applicant: **Manufacturing Resources International, Inc.**, Alpharetta, GA (US)

(72) Inventors: **William Dunn**, Alpharetta, GA (US); **Mike Brown**, Cumming, GA (US)

(73) Assignee: **Manufacturing Resources International, Inc.**, Alpharetta, GA (US)

(**) Term: **15 Years**

(21) Appl. No.: **29/858,211**

(22) Filed: **Oct. 28, 2022**

(51) LOC (15) Cl. **14-03**

(52) U.S. Cl.

USPC **D14/307**; D20/39

(58) **Field of Classification Search**

USPC D14/125, 302, 303, 304, 305, 306, 307, D14/900, 902; D13/162, 163; D10/108; D21/332, 325; D20/10

CPC G06Q 20/18; G06Q 20/10; G06Q 20/108; G06Q 20/1085

See application file for complete search history.

(57) **CLAIM**

The ornamental design for an outdoor electronic display assembly, as shown and described.

DESCRIPTION

FIG. 1 is a front perspective view of the outdoor electronic display assembly;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines depict portions of the outdoor electronic display assembly that form no part of the claimed design. The broken lines on the display portion in FIGS. 1-3 are included for the purpose of illustrating environment and form no part of the claimed design.

1 Claim, 5 Drawing Sheets
